UNITED STATES PATENT OFFICE.

ALBERT HAYES, OF NEW YORK, N. Y., ASSIGNOR, BY MESNE ASSIGNMENTS, TO THEODORE J. LINDLEY.

DEVICE FOR VAPORIZING LIQUIDS.

No. 806,139.

Specification of Letters Patent.

Patented Dec. 5, 1905.

Application filed February 27, 1905. Serial No. 247,514.

To all whom it may concern:

Be it known that I, ALBERT HAYES, a citizen of the United States, residing at New York, in the county of New York, State of New York, have invented certain new and useful Improvements in Devices for Vaporizing Liquids, of which the following is a description, reference being had to the accompanying drawings, and to the figures of reference marked thereon.

My invention relates to devices for vaporizing liquid, and is particularly intended for vaporizing hydrocarbon oils in order to form a combustible gaseous compound suitable for use in explosive-engines or for other purposes.

My invention is designed to overcome certain difficulties which have heretofore been found in the use of the heavier hydrocarbons as the basis for forming gaseous mixtures suitable for use as the explosive charge for explosive-engines.

It is common to make use of the lighter or more volatile hydrocarbons, such as gasoline or naphtha, as the basis of the explosive charge, and the so called "gasoline-engines" are successfully and extensively used. The desirability of using a heavier and less dangerous hydrocarbon as the basis of the charge has been generally recognized, and much time and effort has been expended in the attempt to satisfactorily vaporize the heavier hydrocarbons for this purpose. These attempts have been so far unsuccessful that the engines employing kerosene or other heavy hydrocarbon as the basis of the explosive charge have not gone into extensive use. The difficulties in the use of the heavier hydrocarbons as the basis of the explosive charge appear to be due to the difficulty of properly vaporizing the oil without either vaporizing in a retort which

requires high heat and the use of a discharge-orifice of such size that it is liable to clog, or vaporizing by spraying or otherwise finely dividing the oil, which is liable to result in an excess of the hydrocarbon and consequent deposit of carbon in the engine-cylinder. These difficulties are overcome in the device of my invention by the use of a construction which permits the air employed to take up only the proportion of oil necessary to make

a satisfactory explosive charge. The device is preferably so arranged that the air is first heated and is then caused to take up a slight quantity of oil and a slight quantity of water, the air carrying the oil and the water being then reheated and again caused to take up a

further amount of oil, and it is essential to the operation of the device that the oil be presented in the form of a film to the air-current, so that it will be impossible for more than the desired amount to be taken up. 60

With the above-explained purposes in view my invention consists in the construction and combination of elements hereinafter described, and particularly pointed out in the claims. 65

Referring to the drawings, Figure 1 is a vertical section through the device on line A A of Fig. 3. Fig. 2 is a vertical section through the device on line B B of Fig. 3. Fig. 3 is a top plan view of the device. Fig. 4 is a horizontal section about midway between the ends of the device, and Fig. 5 is a vertical section through the upper head. Fig. 6 is a horizontal section on line C C of Fig. 8. Fig. 7 is a horizontal section on line D D of Fig. 8, 75 Fig. 8 is a vertical section on line E E of Fig. 3.

In the drawings, 1 is a casing preferably, though not necessarily, cylindrical in cross-section, having a passage 2 through it from 80 end to end communicating at one end through pipe 3 with the exhaust of an explosion-engine or other source of heated air or heated gases and having a discharge-pipe 4 connected with its other end. Between the wall of 85 the passage 2 and the outer wall of the casing 1 is formed a pair of passages 5 and 6, preferably spiral, the lower portion of the passage 6 being preferably divided by the partition 6' into two parallel passages. The casing 1 is provided at its ends with heads 7 and 8, having passages 9 and 10, respectively, communicating with the spiral passages 5 and 6, as hereinafter explained. The passages 5 and 6 in the casing with the passages 9 and 10 in 90 the heads form, taken together, a continuous passage or air-conduit leading from the upper head downward through the walls of the casing about the passage 2 to the lower head and thence upward through the walls of the 95 casing about the passage 2 to the upper head. The head 7 is provided, preferably at points about diametrically opposite each other, with openings 11 and 12, of which the opening 11 serves as an inlet-opening for the admission 100 of air and the opening 12 serves as an outlet for the gas formed in the device, as hereinafter described. Pipes 13 and 14 are connected, respectively, with the openings 11 and 12, the pipe 13 leading from a suitable supply of 105

air under pressure of preferably about ten pounds, and the pipe 14 leading to the cylinder of the engine or the receptacle in which the gas is to be stored.

5 In case the device is to be used in connection with a four-cycle engine it will not be necessary to supply air under pressure to the air-inlet 11, as the downstroke of the piston by its suction will create a current of air sufficient 10 for the proper operation of the device.

The casing 1 is preferably, though not necessarily, arranged vertically, as shown, so that the head 7 will be at its upper end and the head 8 at its lower end. The lower head 8 by 15 its passage 10 serves to connect the lower ends of the spiral passages 5 and 6. In the passage 10 is a diaphragm 15, having two openings 16 through it, the diaphragm being so arranged that all communication between the ends of 20 the passages 5 and 6 is necessarily through the openings 16. The openings 18 are alike and only one of them need be described. Each is provided with a valve-seat 17, formed integrally with the diaphragm or preferably, 25 as shown, by a ring set into the opening 16. This valve-seat is tapered, as shown, to form a seat for a conical or tapering valve 18. Surrounding the valve-seat is a groove or well 19, which communicates with the face of the 30 valve-seat by means of small holes or grooves 20, preferably four in number, though the number may be varied. The groove or well 19 communicates by an inlet 21 with a supply-pipe 22, the inlet being controlled by a 35 suitable valve 23. Through one of the supply-pipes 22 oil is supplied to one of the grooves or wells 19, and through the other supply-pipe 22 water is supplied to the other of the grooves or wells 19, the oil or water, as 40 the case may be, passing from the groove or well through the holes 20 to the face of the valve-seat when the valve is lifted.

The valves 18 and 18' are respectively provided with tapered or conical faces 24 and 24', 45 adapted to fit the valve-seats 17 and 17' and above the faces 24 and 24' have, respectively, flanges 25 and 25', adapted to extend over and form covers for the grooves or wells 19 and 19'. Below the faces 24 and 24' the valves 18 50 and 18' are provided, respectively, with a series of inclined downwardly-extending wings or vanes 26 and 26', adapted when a current of air is forced or drawn upward to raise the valve to be so acted on as to cause the valve 55 to be slightly rotated.

The upper head 7 is provided with a diaphragm 15', which, as in case of the diaphragm in the lower head, is provided with one or more openings 16', each provided with a valve 60 18', groove or well 19', supply-pipe 22', and valve 23', the construction being in all respects the same as in case of the corresponding valves in the lower head, with the exception that the valves of the upper head are preferably provided with means for regulating their move- 65

ment. For this purpose in the construction shown the valves 18' are each provided with a head 27 concentric with the valve and adapted to enter a cylindrical opening 28, formed in a plug 29, inserted in an opening 30 directly 70 above the valve 18', and an adjusting-screw 31 extends through the upper end of the plug, so that the upper end of the head 27 will strike its lower end when the valve is raised.

The walls of the passage 2, through which the exhaust from the engine passes, are preferably provided with ribs 32 in order to increase the surface exposed to the heat of the exhaust and to increase the mass of metal, so as to both take up more heat than would be 80 done by a passage with plain walls and to retain the heat longer, and the diaphragms 15 and 15', carrying the valves 18 and 18' and the grooves or wells 19 and 19', are of sufficient thickness of metal and so located 85 with reference to the walls of the passage 2 that they will become sufficiently heated by conduction from the walls of the passage to maintain the oil in the groove or well 19 and 19' at a high degree of heat, preferably at a heat 90 nearly that of the "cracking-point." The valves 18 and 18' are preferably of such weight as to remain on their seats unless by a decrease of pressure above them or an increase of pressure below they are forced upward. 95

In the operation of my device as above described the several pipes 22 and 22' are connected to suitable reservoirs or other supplies of oil or water, as the case may be, one of the pipes 22 of the lower head being connected 100 with a water-supply and the other with an oil-supply, and the pipes 22' of the upper head being, preferably both if two are used, connected with an oil-supply. It is not necessary for the oil or the water to be supplied under pressure, it being necessary only for the oil or water to flow in with sufficient rapidity to keep the grooves or wells 19 full, or nearly so. Air under pressure of preferably about ten pounds enters through the air-inlet 11 and 110 passing downward through the spiral passage 5 is heated by contact with the walls of the casing which are kept hot by the exhaust from the engine passing through passage 2. From the passage 5 the heated air enters the 115 passage 10 of the lower head 8 and by its pressure causes the valves 18 of the lower head to lift slightly, and at the same time, by the action of the air-current on the wings or valves 26, gives the valve a slight rotation to 120 distribute the oil or water, which, as the valve lift is free to pass through the holes 20 from the groove or well 19. The effect of this rotation is to spread the oil or water in a thin film, in which form it is readily taken up by the 125 air-current in its passage through the valve. The currents of air from the two valves of the lower head, one carrying the oil so picked up and the other carrying water, enter, respectively, the passages into which the lower por- 130

tion of the spiral passage 6 is divided by the passage 6', and at the point where these passages unite, mix together, the mixture of air, oil, and water is subjected to the heat of the walls of the passage, by which the vaporization of the oil and water is made complete and the gaseous mixture more or less completely fixed. The heated gas then passes into the upper head 7 and passing through the openings 16' of the diaphragm 15', controlled by the valves 18', takes up a further quantity of oil and then passes through the outlet 12 to the cylinder of the engine. The flanges 25 and 25' of the valves 18 and 18' serve to protect the grooves or wells 19 and 19' while the valves are closed from any back pressure of the gas which might tend to prevent the oil or water from flowing into the groove or well and while the valves are raised leave the grooves or wells open for more or less oil or water to be taken up from the surface of the oil or water in the groove or well. The proportion of oil and water thus taken up by the air is comparatively slight, and no further addition of air is needed to make an explosive charge suitable for use. If desired, the gaseous mixture as it is discharged from the outlet 12 may be subjected to compression to form a practically stable gas suitable for general use, it being necessary only that the compression be intermittent, so that the flow from the outlet 12 will be intermittent and the valves 18 will open and close intermittently.

The device as above described is adapted to be connected with any explosion-engine and is adapted to use for the purpose of forming an explosive charge any liquid hydrocarbon from gasoline or naphtha to the heaviest oils, such as crude oil or fuel-oil, it being necessary only that the oil used be sufficiently fluid to flow into the grooves or wells 19 and keep them full, or nearly so.

If desired, different oils may be used to supply the grooves or wells of the valves of the upper and lower head, or if two valves are used in the upper head one may be supplied with heavy oil and the other with gasoline or other more volatile hydrocarbon.

By means of the device as above described any gasoline-engine may without change other than the substitution of the device for the vaporizer or carburetor commonly used be adapted to be run with kerosene or even fuel-oil or crude oil.

It will be noted that the passages through which the air passes in taking up the oil are of such area that there is no opportunity for clogging by deposit of carbon, and any possibility of clogging is further avoided by the tending of the air-current to clear the valve and its seat.

Having thus described my invention, what I claim as my invention, and desire to secure by Letters Patent, is—

1. In a device for vaporizing liquids, the combination of an air-conduit, a diaphragm in said conduit having therein an air-passage provided with a valve-seat, means for supplying liquid to the valve-seat, a lift-valve for the valve-seat arranged to control the passage of air through the conduit and means carried by the valve adapted to be acted on by air passing through the conduit to rotate the valve to distribute the liquid. 70

2. In a device for vaporizing liquid, the combination of an air-conduit, a diaphragm in said conduit having therein an air-passage provided with a valve-seat, means for supplying liquid to the valve-seat, a lift-valve for the valve-seat arranged to control the passage of air through the air-conduit, the valve being provided with inclined vanes or wings adapted to be acted on by air passing through the conduit to rotate the valve to distribute the liquid. 80

3. In a device for vaporizing liquid, the combination of an air-conduit, a diaphragm in said conduit having therein an air-passage provided with a valve-seat, means for supplying liquid to the valve-seat, a lift-valve for the valve-seat arranged to control the passage of air through the air-conduit, the valve being provided on its under side with inclined vanes or wings adapted to be acted on by air passing through the conduit to rotate the valve to distribute the liquid. 90

4. In a device for vaporizing liquid, the combination of an air-conduit, a diaphragm in said conduit having therein an air-passage provided at its upper end with a valve-seat, means for supplying liquid to the valve-seat, a lift-valve for the valve-seat arranged to control the passage of air through the air-conduit, the valve being provided on its under side with inclined vanes or wings extending into the air-passage adapted to be acted on by the air passing through the conduit to rotate the valve to distribute the liquid. 100

5. In a device for vaporizing liquid, the combination of an air-conduit, a diaphragm in said conduit having therein an air-passage provided with a valve-seat, a groove or well surrounding the valve-seat and in communication therewith, means for supplying liquid to the groove or well, a lift-valve for the valve-seat arranged to control the passage of air through the conduit and means carried by the valve adapted to be acted on by the air passing through the conduit to rotate the valve to distribute the liquid. 115

6. In a device for vaporizing liquid, the combination of an air-conduit, a diaphragm in said conduit having therein an air-passage provided with a valve-seat, a groove or well surrounding the valve-seat and in communication therewith, means for supplying liquid to the groove or well, a lift-valve for the valve-seat arranged to control the passage of air through the air-conduit, the valve being provided with 120

inclined vanes or wings adapted to be acted on by air passing through the conduit to rotate the valve to distribute the liquid.

7. In a device for vaporizing liquid, the combination of an air-conduit, a diaphragm in said conduit having therein an air - passage provided with a valve-seat, a groove or well surrounding the valve-seat and in communication therewith, a lift-valve for the valve-seat arranged to control the passage of air through the air-conduit, the valve being provided on its under side with inclined vanes or wings adapted to be acted on by the air passing through the conduit to rotate the valve to distribute the liquid.

8. In a device for vaporizing liquid, the combination of an air-conduit, a diaphragm in said conduit having therein an air - passage provided at its upper end with a valve - seat, a groove or well surrounding the valve-seat and in communication therewith, means for supplying liquid to the groove or well, a lift-valve for the valve-seat arranged to control the passage of air through the air-conduit, the valve being provided on its under side with inclined vanes or wings extending into the air-passage adapted to be acted on by the air passing through the conduit to rotate the valve to distribute the liquid.

9. In a device for vaporizing liquid, the combination of an air-conduit, a diaphragm in said conduit having therein an air - passage provided with a valve-seat, a groove or well in the upper face of the diaphragm surrounding the valve-seat and in communication therewith, means for supplying liquid to the groove or well, means for heating the diaphragm to heat the liquid in the groove or well, a lift-valve for the valve-seat arranged to control the passage of air through the conduit, and means carried by the valve adapted to be acted on by air passing through the conduit to rotate the valve to distribute the liquid.

10. In a device for vaporizing liquid, the combination of an air-conduit, a diaphragm in said conduit having therein an air - passage provided with a valve-seat, a groove or well in the upper face of the diaphragm surrounding the valve-seat and in communication therewith, means for supplying liquid to the groove or well, means for heating the diaphragm to heat the liquid in the groove or well, a lift-valve for the valve-seat arranged to control the passage of air through the air-conduit, the valve being provided with inclined vanes or wings adapted to be acted on by air passing through the conduit to rotate the valve to distribute the liquid.

11. In a device for vaporizing liquid, the combination of an air-conduit, a diaphragm in said conduit having therein an air - passage provided with a valve-seat at its upper end, a groove or well in the upper face of the diaphragm surrounding the valve-seat and in communication therewith, means for supply-

ing liquid to the groove or well, means for heating the diaphragm to heat the liquid in the groove or well, a lift-valve for the valve-seat arranged to control the passage of air through the air-conduit, the valve being provided on its under side with inclined vanes or wings extending into the air-passage adapted to be acted on by the air passing through the conduit to rotate the valve to distribute the liquid.

12. In a device for vaporizing liquid, the combination of an air-conduit, a diaphragm in said conduit having therein an air - passage provided with a valve-seat, a groove or well in the upper face of the diaphragm surrounding the valve-seat and in communication therewith, means for supplying liquid to the groove or well, a lift-valve for the valve-seat arranged to control the passage of air through the conduit, the valve being provided with a flange extending over and covering the groove or well, and means carried by the valve adapted to be acted on by air passing through the conduit to rotate the valve to distribute the liquid.

13. In a device for vaporizing liquid, the combination of an air-conduit, a diaphragm in said conduit having therein an air - passage provided with a valve-seat, a groove or well in the upper face of the diaphragm surrounding the valve-seat and in communication therewith, means for supplying liquid to the groove or well, a lift-valve for the valve-seat arranged to control the passage of air through the air-conduit, the lift-valve being provided with a flange extending over and covering the groove or well and being also provided with inclined vanes or wings adapted to be acted on by air passing through the conduit to rotate the valve to distribute the liquid.

14. In a device for vaporizing liquid, the combination of an air-conduit, a diaphragm in said conduit having therein an air - passage provided with a valve-seat, a groove or well surrounding the valve-seat and in communication therewith, means for supplying liquid to the groove or well, means for heating the diaphragm to heat the liquid in the groove or well, a lift-valve for the valve-seat arranged to control the passage of air through the conduit, the valve being provided with a flange extending over and covering the groove or well and also provided with means adapted to be acted on by air passing through the conduit to rotate the valve to distribute the liquid.

15. In a device for vaporizing liquid, the combination of a casing having an air-conduit formed therein, a diaphragm in said conduit having two air-passages therein, each provided with a valve-seat, means for supplying different liquids to the two valve-seats, a lift-valve for each valve-seat and means carried by the valves adapted to be acted on by air passing through the conduit to rotate the valves to distribute the liquid.

16. In a device for vaporizing liquid, the

combination of a casing having a passage there-through for a heating medium and having an air-conduit formed therein surrounding the passage for the heating medium, a diaphragm 5 in said conduit having therein an air-passage provided with a valve-seat, means for supplying liquid to the valve-seat, a lift-valve for the valve-seat arranged to control the passage of air through the conduit, and means carried by 10 the valve adapted to be acted on by air passing through the conduit to rotate the valve to distribute the liquid.

17. In a device for vaporizing liquid, the combination of a casing having a passage there-through for a heating medium and having an air-conduit formed therein surrounding the passage for the heating medium, a diaphragm in said conduit having therein two air-passages each provided with a valve-seat, means 15 for supplying liquid to the valve-seats, a lift-valve for each of the valve-seats arranged to control the passage of air through the conduit, and means carried by the valves adapted to be acted on by air passing through the conduit to rotate the valves to distribute the liquid.

18. In a device for vaporizing liquid, the combination of a casing having a passage there-through for a heating medium and having an air-conduit formed therein surrounding the passage for the heating medium, said air-conduit leading downward about the passage for the heating medium and then upward about the passage for the heating medium, a diaphragm near the lowest point of said air-conduit having an air-passage therein provided with a valve-seat, means for supplying liquid to the valve-seat, a lift-valve for the valve-seat arranged to control the passage of air through the conduit, and means carried 25 by the valve adapted to be acted on by air passing through the conduit to rotate the valve to distribute the liquid.

19. In a device for vaporizing liquid, the combination of a casing having a passage there-through for a heating medium and having an air-conduit formed therein surrounding the passage for the heating medium, said air-conduit leading downward about the passage for the heating medium and then upward about the passage for the heating medium, a diaphragm in said conduit near its lowest point provided with a valve-seat, a second diaphragm in said air-conduit near its end having therein an air-passage provided with a valve-seat, 30 means for supplying liquid to said valve-seats, a lift-valve for each of said valve-seats arranged to control the passage of air through the conduit, and means carried by each of the valves adapted to be acted on by air passing through the conduit to rotate the valves to distribute the liquid.

20. In a device for vaporizing liquid, the combination of a casing having a passage there-through for a heating medium and having an

air-conduit formed therein surrounding the 65 passage of the heating medium, said air-conduit leading downward about the passage for the heating medium and then upward about the passage for the heating medium, a diaphragm in the air-conduit near its lowest 70 point having therein two air-passages each provided with a valve-seat, means for supplying oil to one of said valve-seats and means for supplying water to the other of said valve-seats lift-valves for said valve-seats arranged 75 to control the passage of air through the conduit, and means carried by each of the valves adapted to be acted on by air passing through the conduit to rotate the valves to distribute the liquids.

21. In a device for vaporizing liquid, the combination of a casing having a passage there-through for a heating medium and having an air-conduit leading downward about the passage for the heating medium and then leading 85 upward about the passage for the heating medium, a diaphragm in the air-conduit near its lowest point having therein two air-passages each provided with a valve-seat, means for supplying oil to one of said valve-seats and 90 means for supplying water to the other of said valve-seats, a lift-valve for each of said valve-seats, a second diaphragm in said air-conduit near its end having therein an air-passage provided with a valve-seat, means for 95 supplying oil to said valve-seat, and a lift-valve for said valve-seat, each of the valves being provided with means adapted to be acted on by air passing through the conduit to rotate the valves.

22. In a device for vaporizing liquid, the combination of a casing having an air-conduit formed therein, a diaphragm in said conduit having therein an air-passage provided with a valve-seat, a groove or well surrounding the 105 valve-seat and communicating therewith, means for supplying liquid to the groove or well, a lift-valve for the valve-seat, provided with a flange extending over the groove or well and adapted to form a covering therefor 110 when the valve is in its seat.

23. In a device for vaporizing liquid, the combination of a casing having an air-conduit formed therein, a diaphragm in said conduit having therein an air-passage provided with a 115 valve-seat, a groove or well surrounding the valve-seat and communicating therewith, a lift-valve for the valve-seat provided with a flange extending over the groove or well and adapted to form a cover therefor when the 120 valve is in its seat and means for limiting the movement of the valve.

In testimony whereof I affix my signature in presence of two witnesses.

ALBERT HAYES.
